PRINTER'S QUOIN

Samuel Holt, Brooklyn, N. Y., assignor to
Mergenthaler Linotype Company, a corpora-
tion of New York

Application December 29, 1931
Serial No. 583,692

3 Claims. (Cl. 254—40)

This invention relates to quoins, such as are used for locking a column of slugs in a printing galley, and contemplates an improved form of quoin and one which is particularly adapted for locking up very low less-than-type-high slugs in a specially constructed shallow galley. These special galleys and low slugs are of recent development, being intended primarily for the printing of telephone directories and the like (see the 10 Frolander application, Serial No. 490,141, filed Oct. 21, 1930 which is now Patent No. 1,903,507, dated Apr. 11, 1933).

The general object of the present invention is to provide a quoин which will be of light weight yet 15 strong and durable, which is capable of being economically manufactured in standardized form, and which will be thoroughly effective and efficient in operation. With these ends in view, the improved quoин comprises two members normally held together in telescopic relation and adapted to be expanded by movement of the members in opposite directions. Specifically, the quoин consists of an open-end box-like structure or housing, and a block adapted to fit within the 20 housing and held in telescopic relation therewith by springs. An eccentric or cam is also located within the housing in such relation to the two members as to act, when turned by a key, to force the inner member outwardly against the tension 25 of springs pulling inwardly thereon.

In the accompanying drawings, the invention is illustrated merely by way of example and in preferred form, and obviously many variations and modifications may be made therein which will 30 still be comprised within its spirit. It is to be understood, therefore, that the invention is not limited to any specific form or embodiment, except insofar as such limitations are specified in the appended claims.

Referring to the drawings:

Fig. 1 is an assembly top plan view of a five-column galley, and showing four columns of different lengths locked against displacement by quoins constructed according to the present invention;

Fig. 2 is a vertical section taken on the line 2—2 of Fig. 1;

Fig. 3 is a vertical section taken on the line 3—3 of Fig. 1, showing the relation of the quoin to the column of slugs;

Fig. 4 is a disassembled perspective view of the quoin and actuating key, showing by the dot-and-dash lines the blank from which the quoin housing is formed;

Fig. 5 is a perspective view of the blank from which the quoin banking block is formed; and

Fig. 6 is a perspective view of the assembled banking block.

Referring to Fig. 1, the shallow galley A comprises a bottom A¹ and four side walls A², A³, A⁴ and A⁵, the galley being divided into five columns a¹, a², a³, a⁴ and a⁵ by a number of partitions b. These partitions b are secured to the bottom A¹ of the galley and are formed with beaded tops b¹ (see Fig. 2) adapted to fit into notches m formed in the ends of the low slugs M; and at each side A² and A⁴ of the galley, there is provided a corresponding rib b². Due to the fact that columns of different lengths are set up in the galley, it is necessary that the quoins C, used for clamping the slugs in each column tightly together, be backed up sometimes by banking blocks, and in the ordinary galley this is accomplished by filling in the entire space between the end wall of the galley and the quoin with suitable blocks. However, in the type of galley illustrated, a single banking block, such as the block D, is used, having a pin p (Fig. 3) projecting from its underside and adapted to be fitted into one or another of a number of perforations P formed in the bottom A¹ of the galley, these perforations being spaced apart so that the quoin C may always be placed in a position to function effectively.

It should be stated that the present invention is not concerned with the galley and slugs briefly described in the foregoing, nor with a means for locking up columns of slugs in the galley, but rather is confined to the particular construction of the locking quoin C and the banking block D adapted to be used in connection with the galley.

As already stated, the quoin C is composed of two main sections, an outer box-like structure or housing 10 (Fig. 4) and an inner plate-like structure 11, which latter is adapted to fit within the housing 10 and to be held in telescopic relation therewith by a pair of coil springs 12 and 13, an interposed floating cam or eccentric 14 being adapted, upon rotation, to move the inner member 11 antagonistically to the springs 12 and 13 to project the forward end thereof outwardly from the housing 10. In this manner, the quoin C may be expanded varying degrees to lock up a column of slugs, the eccentric being held in its locking position by friction.

The outer box-like structure or housing 10 comprises a solid bottom wall 25, end walls 26 and 27, a rear wall 28, and a top wall 29, the housing being left open at the front. Eyelets 30 and 31 are formed in the rear wall 28 of the housing to

serve as anchors for the rear ends of the springs 12 and 13, respectively, and in order to facilitate the attachment of the springs to the eyelets, the top wall 29 of the housing 10 is formed above 5 each eyelet with an opening 32. Thus, when the quoin is being assembled, the holes 32 permit access to the interior of the housing so that a pair of pinchers or other suitable instruments may be inserted to take hold of the springs 12 and 13 10 and attach them to the eyelets 30 and 31. The top wall 29 of the housing 10 is also formed with a central fore-and-aft slot or opening 33, the purpose of which will later appear.

Although the housing 10 may be manufactured 15 in any suitable manner, it is preferably made from a stamped-out sheet metal blank C¹, such as is indicated by dot-and-dash lines of Fig. 4, which is folded or die pressed into the final form illustrated by the full lines in that figure.

20 The inner member 11 is also preferably stamped in one piece from a sheet of metal, being cut to provide a central curved opening 16 and two fore-and-aft slots 17 and 18, one at each side of the central opening 16, all three extending through 25 the rear edge of the member. At their inner ends, the slots 17 and 18 are provided with cross pins 20 and 21, respectively, which serve as anchors for the front ends of the springs 12 and 13.

30 In assembling the quoin C, the eccentric 14 is positioned in the central opening 16 of the member 11 and the front ends of the springs 12 and 13 anchored to the cross pins 20 and 21. The members 10 and 11 are then telescoped and the rear ends of the springs 12 and 13 attached to the 35 eyelets 30 and 31, the attachment of the springs to the eyelets being facilitated by the openings 32, before alluded to.

When assembled, the eccentric 14 projects rearwardly beyond the rear edge of the member 11 40 and bears against the inner face of the rear wall 28 of the member 10, being held in this position under pressure of the springs 12 and 13, which are always under sufficient tension to maintain the members 10 and 11 in telescopic relation. A key 45 socket 15, centrally located in the eccentric 14, is exposed through the fore-and-aft opening 33 provided in the top wall of the member 10, so that a key K may be inserted in the socket for rotating the eccentric, and so that upon rotation the 50 key will be free to reciprocate in the opening 33 as required by the throw of the eccentric.

In order that the eccentric 14 may be rotated in but one direction, it is formed with two oppositely located lugs 40 and 41, one of which will 55 bank against an abutment 42 formed in the wall of the opening 16, dependent upon which lug happens to be located adjacent the abutment at the time of assembly.

60 Referring to Figs. 5 and 6, the adjustable banking block D is preferably stamped in one piece from a sheet of metal and folded to form a hollow rectangular block, open at opposite ends and having parallel top and bottom walls 45 and 46, respectively, a back wall 47, and a partially open 65 front wall formed by three lips 48, 49, and 50, which are bent at right angles to the top wall 45 and have their ends engaging the upper face of the bottom wall 46. When the blank for the block D is stamped out, two circular holes 51 and 52 are 70 cut in the top and bottom walls 45 and 46, respectively, so as to be in vertical alinement when the blank is folded to make up the block. These holes 51 and 52 are adapted to receive and hold the pin p, which projects below the bottom wall 46 so 75 that it may fit in one or another of the perfora-

tions P formed in the bottom A¹ of the galley. The bottom wall 46 of the banking block D is extended at opposite ends, as at 53 and 54, beyond the ends of the top wall 45, so as, when the banking block is placed in the galley, to lie below 80 the beaded heads b¹ of the dividing rails or partitions b and the side rails b² and prevent vertical displacement of the banking block D when the quoin C is expanded to lock up the column of slugs.

Because of its small size, and in order to maintain a high degree of efficiency, the throw of the eccentric 14 is not very great, and under these circumstances it would ordinarily be necessary to locate the perforations P in the bottom of the galley quite close together in order to take care 85 of all varying column lengths. To overcome this necessity (as a result of which the galley bottom between the perforations would be considerably weakened), the pin p is located off center of the banking block D, whereby the latter may be 90 placed in the galley with either its front wall, consisting of the lips 48, 49 and 50, or its rear wall 47 in position to be banked against by the quoin C, as shown in columns a⁴ and a⁵ in Fig. 1.

95 Since the columns of slugs to be locked up 100 are not always of the same length, it has heretofore been necessary to employ furniture to build up the columns between the backs of the quoins and the end of the galley, but according to the construction of the galley with which the 105 improved quoin and banking block are used, the banking block is adjustable in the galley. Thus, if a short column of slugs, such as column a³ shown in Fig. 1, is to be locked up, the quoin C and the banking block D are placed in the column 110 with the pin p seated in one of the upper perforations P, so that there is only a small space, such as indicated at s, between the last slug M of the column and the forward end of the inner member 11 of the quoin C. The banking block 115 D fits in the column with the extensions 53 and 54 of the bottom wall 46 thereof engaging between the beads b¹ of the partitions b in substantially the same manner as the lower portions m of the opposite ends of the slugs M (see 120 Fig. 2), thereby preventing any upward displacement of the banking block when pressure is applied thereon in locking up the column of slugs.

To expand the quoin C for locking up the column of slugs, the key K is inserted in the socket 125 15 formed in the cam or eccentric 14 and turned in a clockwise direction so that the eccentric will force the inner member 11 antagonistically to the springs 12 and 13 up against the column of slugs N, whereby the latter will be locked 130 firmly in place until the eccentric is manually released.

135 It will be noted that in some cases, as when the column of slugs is of full length, such as column a², the banking block D is unnecessary, the quoin C banking directly against the end wall A⁵ of the galley A.

As stated before, the invention is illustrated merely in preferred form and by way of example, and obviously many variations and modifications 140 may be made therein without departing from its spirit. For example, the quoin and banking block have been illustrated and described as small and particularly adapted for use in connection with low slugs and a specially constructed 145 galley, but with little or no modification they may be readily adapted for use with regular or full type-high slugs and galleries. It is to be understood, therefore, that the invention is not to be limited to any specific form or construction 150

- except insofar as such limitations are specified in the appended claims.
- Having thus described my invention, what I claim is:
- 5 1. In or for a printer's galley, a locking quoin comprising a member formed by stamping a blank from a sheet of material and folding the blank to form a box-like housing, a member stamped from another piece of material and adapted to fit within the other member, a pair of coil springs attached at opposite ends to said members and tending to draw them together, and an eccentric located between the two members and adapted to be actuated to force the inner member outwardly against the action of the springs, the second mentioned member being formed with a central curved aperture in which the eccentric is adapted to fit and an aperture at each side of the central aperture in which the springs are located, the side apertures being provided at their inner ends with pins adapted to serve as anchors for the springs. 80
- 10 2. In or for a printer's galley, a locking quoin comprising two members arranged in telescopic relation, the inner member being formed with a curved central opening and two elongated lateral openings, an eccentric adapted to be rotatably arranged in the central opening with a portion of its surface projecting therefrom beyond the edge of the member, a pair of tension springs adapted to be arranged in the lateral openings, means for anchoring one end of said springs in said openings, and means on the outer member for anchoring the opposite ends of said springs to hold the parts in operative relation. 85
- 15 3. In or for a printer's galley, a locking quoin comprising a member formed by stamping a blank from a sheet of material and folding the blank to form a box-like housing, a member stamped from another piece of material and adapted to fit within the other member outwardly against the action of the springs, said box-like housing having top and bottom walls, end walls, and a rear wall, the rear wall having eyelets formed therein near its opposite ends and adapted to anchor the rear ends of the springs, and the top wall having openings formed therein above the eyelets to facilitate the attachment and detachment of the springs and eyelets. 90
- 20 2. In or for a printer's galley, a locking quoin comprising a member formed by stamping a blank from a sheet of material and folding the blank to form a box-like housing, a member stamped from another piece of material and adapted to be actuated to force the inner member outwardly against the action of the springs, said box-like housing having top and bottom walls, end walls, and a rear wall, the rear wall having eyelets formed therein near its opposite ends and adapted to anchor the rear ends of the springs, and the top wall having openings formed therein above the eyelets to facilitate the attachment and detachment of the springs and eyelets. 95
- 25 2. In or for a printer's galley, a locking quoin comprising a member formed by stamping a blank from a sheet of material and folding the blank to form a box-like housing, a member stamped from another piece of material and
